UNITED STATES PATENT OFFICE.

WILLIAM C. FOLEY, OF WORCESTER, MASSACHUSETTS.

PIN-POINT GUARD.

1,177,611.

Specification of Letters Patent.

Patented Apr. 4, 1916.

Application filed March 17, 1913. Serial No. 755,031.

To all whom it may concern:

Be it known that I, WILLIAM C. FOLEY, of Worcester, in the county of Worcester and State of Massachusetts, have invented 5 certain new and useful Improvements in Pin-Point Guards, of which the following is a specification.

This invention relates to hat pin point protectors; and it has for its primary object 10 the provision of a housing member formed of separable sections and accommodating yieldable gripping devices whereby the tension of said devices against the pin may be regulated on adjusting sections of the housing relatively.

With the above and other objects in view, the invention consists of certain novel features of construction, combination and arrangement of parts, as will be hereinafter 20 described and claimed.

In the accompanying drawings:—Figure 1 is a side view of the protector; and Fig. 2 is a longitudinal section therethrough.

The protector comprises a housing 1 25 formed of companion substantially cylindrical sections 2 and 3, the former being open throughout and having its walls provided in a portion of their length with a thread 4 for receiving a corresponding external thread on a portion of the section 3. The section 3 is thus adapted to be inserted 30 in the section 2 in such manner that one end of the latter will be closed while the opposite end will be open to permit of the required insertion in or removal of the pin 35 from the housing, as will be understood. The outer end of the section 3 is provided with a manipulating head 5, whereby said section may be turned in the mating section 40 2 for a purpose to be hereinafter explained.

The section 3 is provided with a relatively long substantially conical passage 6, while at diametrically opposite points within the section 2 are mounted companion gripping 45 devices 7, which are preferably in the form of flat springs having free ends extending beyond the outer end of the section 2 and arranged in the passage 6 of the section 3

and provided with free effective gripping ends 8 which bear directly against the adjacent flared walls of the passage 6.

From this construction, it is apparent that the two sections 2 and 3 of the device may be adjusted relatively, so as to cause the flared walls of the passage 6 to bear against the mentioned free ends of the gripping devices 7, so as to regulate the tension of the devices and cause said free ends to bear effectually against the adjacent point of the pin and hold the point operatively concealed in the housing. The walls 9 of the section 3 merge directly onto the inner walls of the section 2 of the housing so as to provide an unobstructed path to the movement of the pin.

65

I claim:—

A pin protector comprising in combination, male and female tubular members, each of said members being of uniform diameter throughout its length, said female member 70 having a uniform bore opening at both ends of the member and interiorly threaded, a head on said male member, the male member being exteriorly threaded and adjustably associated with the bore of said female member, and having a conical-shaped bore with its small end extending toward the head of said member, a pair of longitudinally extending diametrically opposed leaf springs having one end fixed within the bore of the 75 female member beyond the threaded portion thereof, said springs being convergently disposed and having their free ends arranged normally in contacting engagement with the small end of said conical bore, and said 80 springs being mounted for adjustment toward and away from each other transversely of said protector upon adjustment of said 85 male and female members.

75

In testimony whereof I have affixed my 90 signature, in presence of two witnesses.

WILLIAM C. FOLEY.

Witnesses:

EDWARD T. DUNNE,
ALBERT SHRAGER.
